GUANO DISTRIBUTOR

Eugene M. Cole, Charlotte, N. C.

Application May 4, 1932. Serial No. 609,082

6 Claims. (Cl. 221—130)

This invention relates to a guano distributor having a rotary member disposed therein and having means for forcing into said rotary member and out of the same to the exterior of the hopper a definite measured quantity of guano regardless of the state of the guano as to fineness and moisture contents.

An object of this invention is to provide a guano distributor having a rotary member provided with a peripheral annular space and means for forcing guano into said annular space, together with means for forcing the guano from the annular space to the exterior of the hopper, said distributing means being adapted to maintain at all times a definite quantity of free guano in the annular space so that the amount of guano expelled from the hopper will be constant at all times regardless of the condition of the guano.

20 The structure shown herein is somewhat similar to the structure in my co-pending application, Serial Number 571,648, filed October 28, 1931, and in which application I have elected to retain the broader claims.

25 Some of the objects of the invention having been stated, other objects will appear as the description proceeds when taken in connection with the accompanying drawings, in which—

Figure 1 is an elevation of my guano distributor;

Figure 2 is an enlarged view of the gears which are attached to driving wheel with housing removed, showing means for throwing distributor in and out of gear;

30 Figure 3 is a sectional view taken along line 3—3 in Figure 2, thru gear housing attached to driving wheel;

Figure 4 is a sectional plan view of the guano hopper and associated parts;

40 Figure 5 is a vertical sectional view taken along line 5—5 in Figure 4;

Figure 6 is an inverted plan view of the guano hopper;

45 Figure 7 is an elevation of a rear portion of the guano hopper showing opening and means whereby guano is deflected from the hopper.

Figure 8 is a detail view showing a front elevation of a portion of the deflector and the sidewall of the hopper and the two disks forming 50 annular space 110.

Referring more specifically to the drawings, the numerals 10 and 11 indicate the two members forming the beam or the main portion of the framework of the guano distributor having 55 a draw bar 12 secured between the front ends

thereof in which is mounted a draft ring 13. A depth regulating member 14 is secured between the members 10 and 11 and has a drag 15 secured on the lower end thereof with a brace 16 secured to member 14 and having a slot 17 in the upper end thereof penetrated by a bolt 18 penetrating the beam portions 10 and 11 for the purposes of adjusting the depth of the plow 19 secured to the lower end of foot member 20 which member is secured by any suitable means such as bolts 65 21 and 22 to hold the foot member rigidly between the beam members 10 and 11. Bolt 22 also secures handle portions 23 at their lower ends to the beam members 10 and 11. Handle members 23 project upwardly and rearwardly 70 and have secured thereto by any suitable means such as bolt 24 and upper end of braces 25, the lower end of said braces being secured to beam members 10 and 11 for supporting the handles 75 in a rigid position.

Suitable downwardly projecting members such as 26 are secured to the rear end of beam members 10 and 11 (there being only one of these members shown). These members are secured 80 by any suitable means such as bolts 27, piercing the downwardly extending members 26, the vertically inclined brace 25, and also the beam members 10 and 11. Between these downwardly projecting members 26 is mounted a traction or ground wheel 28 having an axle 29 which projects thru bearing portion 30 of member 26, and is squared at one of its ends and has removably mounted thereon a pinion 31 which pinion is adapted to mesh with another pinion 32 rotatably secured on a sleeve 33, which sleeve is 85 threadably secured on bolt 34, and this sleeve has a base portion 35 having lips 36 and 37, said lips of base portion fitting tightly against gear lever 38 to prevent relative movement between sleeve 90 member 33 and member 38. Pinion 32 has an 95 extension 39 which is hexagonal in cross-section. Removably mounted on this hexagonal portion is a sprocket wheel 40, the sleeve portion 39 of pinion 32 and sprocket wheel 40 being confined on bolt 34 by means of a washer 41 and cotter pin 42.

The upward and downward movement of lever 38 to throw pinion in and out of gear is accomplished by means of a rod 50 which pierces gear lever 38 and is secured thereto by any suitable means such as cotter key 51. Rod 50 extends upwardly and is secured to plate 51a, said plate being pivotally mounted on member 52. Plate 51a also has attached thereto a rod 53 which is 105 pivotally attached to lever 54 as at 55 which lever 110

is pivotally mounted to handle 23 by any suitable means such as bolt 56; therefore, it is evident that when lever 54 is pulled forward or backward rods 50 and 53 are moved at the same time and lever 53 38 is respectively lowered or raised to throw the mechanism in or out of gear.

In Figures 2 and 3 the device is shown out of gear with the distributing mechanism, and when the handle 54 is released as in Figure 1, 10 pinion 32 is allowed to drop downwardly and the mechanism is thrown in gear. Projection 48 will limit this downward movement. When handle 54 is raised past dead center the weight of rod 50 and associated parts will hold handle 15 54 above dead center and hold gear 32 in raised position.

Sprocket wheel 40, sleeve 33 and pinion 32 are secured by means of bolt 34 to gear lever 38 which is secured to portion 43 by any suitable 20 means such as bolt 44 so that the lever can be lowered or raised, thereby throwing the pinions in and out of gear. Said portion 43 is adjustably mounted on beam portion 10 by means of bolt 57 penetrating slot 58. A suitable cover 25 45 is secured over the pinions 31 and 32 by any suitable means such as bolts 46, 46a and 47 penetrating member 26 and cover 45 and also bolt 27 which penetrates members 10, 25, 26, and cover 45. Projections 64, 61, 62, 63 are also provided on member 26 to hold cover 45 in proper 30 position while bolts 46, 46a, 47 and 27 are being tightened. Cover 45 has an opening 60 thru which the extension portion 33 of pinion 32 projects, this opening being large enough to provide ample clearance for vertical movement of extension portion 33 when pinions are thrown in 35 and out of gear.

A projection 48 is provided on member 26 on which beveled portion 49 of gear lever 38 is 40 adapted to rest when the pinions 31 and 32 are engaged. A projection 49 is also provided on member 26 to hold lever 38 in its proper position in order that there will be very little lateral play in lever 38 and pinion 32.

45 Since pinion 31 revolves in a clockwise motion it is readily seen that when pinion 31 engages pinion 32 the rotating movement will tend to hold beveled portion 49 firmly against projection 48, thereby preventing gears from becoming disengaged while the distributor is in operation.

Sprocket wheel 40 has mounted thereon a sprocket chain 65 which is also mounted on sprocket wheel 66, removably mounted on sleeve 67 which sleeve is hexagonal in cross section, and sprocket 66 has a hexagonal hole therein for loosely fitting over the sleeve 67. Sleeve 67 has integral therewith a beveled gear portion 68. The sleeve 67 and beveled gear 68 are rotatably mounted on pin 69 which is integral with arm 60 70. The sprocket wheel 66 and the beveled gear 68 with its sleeve 67 are confined on pin 69 by means of washer 71 and cotter pin 72. Arm member 70 has projections 73 fitting closely to beam portion 10, said member 70 being fastened to member 10 by any suitable means such as bolts 74. Sprockets 40 and 66 are interchangeable. By a minimum number of sizes of such sprockets a great number of rates of flow of guano can be effected.

70 Beveled gear 68 is adapted to mesh with a larger beveled gear 75 fixedly mounted on shaft 76 which shaft has a square cross section, and gear member 75 has a square hole in the center thereof for loosely fitting over shaft 76.

75 Beveled gear member 75 and fixed member

79 have sliding surfaces 77 and 78 upon which gear member has sliding contact when shaft 76 turns. Fixed member 79 also has bearing surfaces 80 and 80a on the upper side thereof which are adapted to slide against the lower portion of circular plate 81 which plate is attached to the lower side of head portion 82 of shaft 76 and having bent-up portions 83 at ninety degree intervals on the plate, the function of portions 83 being to come in close contact with walls of hopper 84 and prevent any damp guano from accumulating on the sides and thereby reducing the volume of fertilizer distributed.

On the upper side of head portion 82 is another circular plate 87 secured to said portion 82 by means of bolts 88, 89, 90, 91 which bolts penetrate plates 87, 81 and portion 82 and bind them securely together so there will be no relative movement. Bolts 88 and 90 also penetrate angle member 92 and secures it to the top of plate 87 and this member 92 has bent up portion 93 whose function is to revolve with shaft 86 and its associated parts and to force the fertilizer into the annular space between plates 81 and 87.

100 It would appear to be difficult to have a deflector fixed on the hopper and projecting into annular space 110 and yet not be in the path of rotation of portions 83. By referring to Figure 8, it is seen that this difficulty is solved by 105 having the portion 104b of member 104 projecting into the hopper 84 thru opening 113 and having vertically disposed portion 103a of deflector secured thereto, which portion 103a occupies a position inside the circle described by 110 scrapers 83.

Bottom portion 79 has a projection 79a extending beyond the outside of lower portion of hopper 84 which has a cavity 79b in which portion 104a of member 104 has limited vertical 115 movement on bolt 107 as a pivot, but is prevented from lateral movement. This vertical movement of deflector 103 is provided to prevent friction being applied to the deflector should some guano collect below plate 81 and force the 120 same upward out of its regular plane. A space 83a is present between portion 79a and portion 103a through which the scrapers 83 pass.

The deflector arrangement whereby the scrapers 83 are unobstructed in their rotary movement is made possible by making the upper plate 87 smaller than the lower plate 81 so that by referring to Figures 5 and 8 it is seen that sufficient space exists between the scrapers 83 and the periphery of plate 87 for allowing portion 103a to be out of the path of scrapers 83 and plate 87.

125 Shaft 76 and its associated parts are secured to fixed member 79 by means of washer 85 and cotter key 86. Fixed member 79 has vertically disposed braces 94 and 95 holding it rigidly to beam members 10 and 11 by any suitable means such as bolts 96, 96a, 97, 97a, 98 and 99 and upon the inner circumference of member 79 a hopper plate 84 is held closely to the inner circumference 140 by means of bolts such as 96, 96a, 97 and 97a penetrating hopper plate 84, fixed member 79 and vertical braces 94 and 95.

145 The plates 81 and 87 being of larger diameter than the intermediate portion 82 leave a circumferential groove or annular space 110 into which the guano is forced by the upright flanged portion of member 92 and expelled therefrom by member 103. The guano is forced into this 150 groove 110 by means of top plate 87 having there-

in a plurality of radially disposed slots 111 forming tongues 112.

Hopper 84 has a suitable opening 113 therein thru which the guano is expelled into spout 115 which is secured to beam members 10 and 11 by any suitable means such as bolt 99 and likewise secured to foot member 20 by means of strap 100 and bolt or rivet 101. The interior of the hopper 84 has secured thereto a cover member 102 by means of bolts or rivets 108, 109, which screens the opening 113 and prevents the guano from coming out at opening 113 except the guano which is forced out of groove 110 by means of deflector 103.

Deflector 103 projects thru opening 113 and into groove 110 so that as member having plates 81 and 87 is rotated the guano will be forced down between slots 111 and will be forced out of groove 110 thru opening 113 and down thru spout 115. This deflector 103 is secured to member 104 by any suitable means such as bolt 105 and member 104 is adjustably mounted on the outside of hopper plate 84 by means of bolt or screw 107 penetrating slot 106 and plate member 84. The deflector 103 is adapted to scrape the under surface of plate 87 and the top surface of plate 81, and portion 83 of plate 81 is adapted to scrape the portion of the hopper which forms the outer wall of the groove or annular space 110. Thus, the volume of free fertilizer contained in annular space 110 is constant at all times and the volume of guano expelled is accurately measured at all times, regardless of the condition of the guano as to moisture content or size of its particles.

One of the main advantages of this guano distributor is the interchangeability of the sprockets 40 and 66 so that by the use of a limited number of sizes of sprockets the rate of flow of guano can be regulated. An important feature of this invention is that a definite quantity of guano is forced thru the openings 111 into the annular space 110 and therefore regardless of the condition of the guano a definite quantity will be delivered regardless of the moisture content of the guano. Furthermore, the portions 112 cut lumps of guano into small pieces so as to not interfere with the proper distribution of the guano regardless of its state of fineness. A most important feature of this invention is the fact that all of the surfaces enclosing the groove or annular space 110 are scraped continuously so that the volume of free fertilizer contained in said space is constantly the same and the volume of fertilizer expelled by deflector 103 is constantly the same regardless of the kind of fertilizer, its condition, and physical properties.

In the drawings and specification there has been set forth a preferred embodiment of the invention and although specific terms are employed they are used in a generic and descriptive sense only and not for purposes of limitation, the scope of the invention being set forth in the appended claims.

I claim:

1. In a guano distributor, a framework, a hopper secured on the framework, a bottom member secured to the bottom of said hopper and having a hub portion centrally disposed therein and having a vertically disposed hole forming a bearing, a rotatable bottom member having a downwardly projecting spindle, a gear secured to the lower end of said spindle, means for driving said gear, said rotatable bottom member comprising upper and lower spaced plates, a plurality of projec-

tions extending upwardly from the lower plate in close proximity to the inside wall of the hopper for scraping guano from said inside wall, said hopper having an opening in one side thereof adjacent said rotatable member and a deflector secured to said hopper and projecting into the space between the plates for deflecting guano from the hopper, the upper plate having openings therein to admit guano to the space between the plates.

2. In a guano distributor having a stationary hopper, a bottom member secured to said hopper and having a centrally disposed hub portion with a vertically disposed perforation therein serving as a bearing, a rotatable member mounted in said hopper, comprising spaced upper and lower disks, the upper disk having openings therein to admit guano into the space between the plates, projections on the lower disk moving in close proximity to the sidewalls of the hopper for scraping guano therefrom, a spacing member disposed between the two disks and having a spindle projecting downwardly and occupying a position in said bearing in said hub portion, means for securing said spindle in said bearing member, a gear member secured on the lower end of said spindle, a second gear engageable with said first gear for driving the same, said hopper having a hole in one side thereof, a deflecting member secured on the exterior of said hopper and projecting thru said hole and into the space between the two said disks for deflecting guano from the hopper and scraping proximate surfaces of said disks.

3. In a guano distributor having a hopper, a pair of spaced upper and lower disks mounted in said hopper, the upper plate having openings therein, a spacing member disposed between said disks, projections disposed along the periphery of the lower of said disks for scraping guano from the sidewalls of the hopper, the spacing means between the said disks having a downwardly projecting spindle, a bottom member secured to said hopper and having a bearing portion therein for said spindle, a gear wheel secured to the lower end of said spindle, and a gear member meshing with said first gear for imparting rotation to the said spaced disks, said hopper having a hole in the lower side portion thereof and a deflecting member mounted on said hopper and projecting thru said hole and into the space between said disks for deflecting guano therefrom and for scraping the proximate surfaces of said disks.

4. In a guano distributor having a stationary hopper, a bottom member secured to said hopper and having a bearing portion centrally disposed thereof, a pair of spaced upper and lower disks mounted in the lower portion of said hopper, a spacing member disposed between said disks and the lower plate having a downwardly projecting spindle mounted in said bearing, a gear wheel secured on the lower end of said spindle, means for driving the gear wheel, the upper of said disks having a plurality of radially disposed slots therein, thru which the guano is forced, the lower of said discs having upturned barbs along the outer edge thereof for engaging the sidewall of the hopper and scraping guano from said sidewall, said hopper having a hole, a deflecting member secured on the exterior of the hopper and projecting thru said hole and between said disks for expelling guano from the hopper and scraping the inside surface of said disks.

5. In a guano distributor, a hopper, a rotary member disposed in the bottom portion of said hopper, said rotary member having an annular peripheral cavity therein and having openings 5 in the upper portion thereof communicating with the annular cavity, said hopper having an opening in the side thereof, a deflector secured to the outside of the hopper and extending thru said opening above said rotary member and 10 then projecting downwardly within the circle defined by the lower portion of said rotary member and outside the circle defined by the upper portion of said rotary member and then into said annular cavity, the lower portion of said 15 rotary member having upwardly projecting scrapers thereon adapted to travel outside and beneath the outer portion of said deflector.
6. In a guano distributor having a hopper, a rotary member mounted for rotation in the bot-

20

tom of said hopper, said rotary member being composed of two spaced upper and lower plates, the upper plate being smaller than the lower plate and having a plurality of radially disposed slots therein and the lower plate having upturned scrapers integral with the outer portion thereof, a vane secured to the top portion of the upper plate for forcing the guano thru said radially disposed slots and into the space between the plates and a deflector secured to the hopper, said hopper having a hole thru which the deflector projects, said deflector projecting into said opening and then projecting downwardly inside the circle defined by the periphery of the lower plate and outside the upper plate whereby the scrapers will not engage the deflector.
